REFRIGERATING APPARATUS

John Kirgan, Easton, Pa., assignor to Ingersoll-Rand Company, Jersey City, N. J., a corporation of New Jersey

Application June 6, 1934, Serial No. 729,200

1 Claim. (Cl. 257—28)

My invention relates to refrigerating means and particularly to refrigerating apparatus adapted to save power costs in practical operation.

5 In water vapor refrigeration, the water enters a vessel called an evaporator and is chilled by partial vaporization therein, the vapor being removed to be liquefied in a condenser. For the sake of discussion the evaporator and condenser 10 are assumed to consist of a single chamber each. The condenser is cooled by water, and whenever steam can be had at ordinary expense, to carry the vapor from the evaporator into the condenser, a steam ejector can be employed. The 15 pressure in the evaporator is reduced enough to enable vaporization of some of the water to occur easily at a selected temperature of the incoming water. The pressure in the condenser is also low, but is greater than the pressure in 20 the evaporator, and therefore the condenser exerts some resistance or back pressure to the admission of the steam and water vapor into it. The greater this back pressure, the more steam is required. To save steam, and at the same 25 time obtain from the condenser water the maximum cooling effect without having to employ an excessive amount of such water, is the chief object of this invention. If the cooling water for the condenser is small in volume with respect to 30 the load, the water will be warmed too much in the condenser and the back pressure will be high. This will necessitate a great quantity of steam to force the water vapor into the condenser chamber. Also, if to lower the back pressure 35 and reduce steam, the temperature of the condensing water is kept from rising very high in relation to the amount of liquefaction produced by the condenser, too much water will have to be supplied.

40 My aim is to produce a refrigerating apparatus that will afford economy of both steam and condenser water, and still have a refrigerating output as large as desired. The preferred embodiment comprises an evaporator and a condenser having several chambers each. In the evaporator the water is chilled in stages, passing from one chamber to another and the water vapor is taken out of each chamber in the evaporator and delivered to a corresponding 45 chamber of the condenser. The cooling water flows from each chamber of the condenser to the next, and its warmth is greatest in the chamber near the outlet of the water from the condenser. In this particular chamber the back 50 pressure and temperature may be somewhat

high, while in the preceding chambers the back pressures and temperatures are less. Likewise, in the evaporator chamber where vaporization first takes place the pressure is highest, and it falls off in each succeeding chamber as the process of vaporization and chilling continues.

The steam ejectors are in multiple and so arranged that they connect the evaporator chamber of the first stage, wherein vaporization commences, to the condenser chamber of the last 10 stage which receives the cooling water just before it leaves the condenser, and so on through the series. Hence the ejectors work at successively lower intake and discharge pressures, but the ratio of compression between each evaporator chamber and its associated condenser chamber is substantially constant.

Thus, with both evaporation and liquefaction accomplished by stages, less steam is expended than when the same quantity of water is chilled 20 to the same extent in one evaporator chamber, connected to a single condenser chamber through which water flows in the volume required to permit no more increase in condensing water temperature than the total increase in 25 the condenser used with my invention. Also a great deal less cooling water is taken than if a condenser having one chamber is used, and the cooling water is in such amount with the inlet and outlet temperature fixed so that the back 30 pressure in said chamber is no greater than the lowest back pressure in the sectional condenser above described. The saving in steam is of course the principal consideration, but both steam and cooling water are thus reduced to a 35 minimum.

The nature and advantages of the invention are set forth in the description that follows; but the disclosure is by way of example only, and changes may be made without departing from 40 the spirit of the invention or exceeding its scope.

On the drawing Figure 1 is a view mostly in section showing apparatus according to the invention, and

Figure 2 shows a detail thereof.

The numeral 1 indicates an evaporator to which water to be chilled is supplied by a pipe 2. The evaporator is divided so that it contains a number of chambers 3, 4, 5 and 6. The water from the pipe 2 first enters the chamber 3 and 50 passes thence in succession to the other chambers, and in each of these chambers a portion of the water is converted into vapor. The process of vaporization extracts enough heat from the remainder of the water to cool it, and 55

thus the temperature of the water is lowered step by step as it passes from one of these chambers to the next. The water vapor is removed from each chamber and transferred to a condenser 1 by means of evacuators such as steam ejectors, steam jet boosters or thermocompressors 8. These evacuator members are in parallel, one being connected to each of the chambers of the evaporator and discharging into a corresponding chamber of the condenser, indicated by the numerals 3', 4', 5' and 6', the vapor in the chamber 3 being transferred to the chamber 3', that formed in the chamber 4 being forced into the chamber 4', etc.

15 In the evaporator 1 chilled water to each chamber 4, 5 and 6 is delivered by the chamber immediately above or ahead of it, with reference to the direction of flow through the evaporator 1, through the bottom 9 by way of a delivery nozzle 10, which may be of the spray type. A suitable delivery nozzle may also be attached to the pipe 2 inside of the chamber 3 so that the water may be divided as it enters each chamber, and thus the vaporization is facilitated. After being successively chilled in the chambers of the evaporator the water is discharged through an outlet pipe 11.

20 The ejectors are connected to the evaporator by means of pipes 12, one of these pipes leading to each chamber at the top thereof. These pipes communicate with the main casing of each ejector through an opening in the side thereof, and these casings receive steam through nozzles 13 connected to steam pipes 14. The 25 ejectors discharge into the chambers 3', 4', 5' and 6' of the condenser through ports 15. These ejectors may be of any suitable construction. The steam nozzles 13 are disposed so that when 30 steam issues therefrom, the water vapor is drawn by aspiration from the chambers of the evaporator and entrained with the steam and carried into the chambers of the condenser, where the mixture of steam and vapor is liquefied.

35 45 The chambers of the condenser are separated from one another by means of transverse partitions 16 and through these partitions and the ends of the condenser extend cooling pipes 17 which communicate with headers 18 at the 50 ends of the condenser. To one of these headers cooling water is supplied, and from the other cooling water is discharged. As shown in Figure 1, the cooling water passes in at the bottom and out at the top, cooling the chamber 6' first and the others in succession. Thus the direction taken by the cooling water in the condenser is opposite to that of the water to be chilled in its flow through the chambers of the evaporator. The condenser cooling water is at its lowest 55 temperature where it enters the condenser and is warmest where it leaves the condenser. The temperature and back pressure in the chamber 6' are therefore relatively low, but are successively higher in the other condenser chambers 60 and greatest in the chamber 3'. But in the evaporator 1 the water to be cooled has its highest temperature in the chamber 3 and its lowest temperature in the chamber 6. Likewise the pressure drops in the same way, being lowest in 65 the chamber 6 and greatest in the chamber 3. The suction pressure for the ejectors connected to the chambers 3, 4, 5 and 6 thus becomes successively lower and similarly the back pressure against which these ejectors work becomes successively lower in the corresponding chambers 70 75

3', 4' 5' and 6'. The water vapor from all the evaporator chambers can thus be compressed by the ejectors in the same ratio as this vapor is delivered to the condenser 1. This results in 5 detail later.

The chamber 6' of the condenser which is first cooled by the condenser water has connected thereto a conduit 19 in the line of which is a vacuum or purge pump 20. The various 10 condenser chambers are joined by means forming vent passages 21 connecting one chamber to the next one above it, so that the purge pump 20 exhausts the various condenser chambers in series. Valves 22 in the vent passages 21 control the bore of these passages, so that by the action of the pump exhausting device 20, a 15 vacuum of different degree can be maintained in each of the condenser chambers.

The various chambers of the condenser are 20 also connected by members 23 enclosing U-shaped trap passages 24 which connect the lower part of each condenser chamber to the top part of the next chamber beneath. Each of these passages 24 has the middle or bend thereof at a lower level than the two ends of this passage. The water of condensation can drain freely from the upper chambers of the condenser down to the lowermost chamber, while at the same time these passages seal the 30 chambers from one another because of the liquid in the bends thereof. Otherwise the internal pressure of each of these chambers would be the same. The lowermost chamber has a drain pipe 25, in the line of which is a discharge 35 pump 26 to carry off the condensate from the condenser.

In operation, the pressure in the chamber 3 is so reduced by the action of the evacuator 8 that some of the water is converted into vapor 40 at once. The formation and removal of this vapor results in chilling the remainder of this water, the vapor and steam being impelled into the condenser chamber 3', while the unvaporized water is delivered into the next chamber 4 45 through the nozzle 10. In this chamber 4 the pressure is somewhat lower and more water is vaporized so that the remaining water is chilled still further. The water is thus cooled by stages in the evaporator and reaches its lowest temperature in the chamber 6, from which it is 50 discharged through the pipe 11.

Suppose the water delivered by the pipe 2 has a temperature of 70° F., and the absolute pressure in the chamber 3 is about .635 inches of 55 mercury. Under these conditions enough water can be converted into vapor to bring down the temperature of the remaining liquid water to about 65.5° F., as it flows into the chamber 4. In this chamber the pressure will be slightly lower, 60 say, about .54 inches of mercury. The water flowing from the chamber 4 into the chamber 5 will thus be cooled down to about 61° F. In this chamber 5 the pressure will be about .46 inches of mercury and the water may be cooled down 65 to about 56.5° F. Next in the chamber 6 the pressure will be, say, .4 inches of mercury and the final temperature of the water leaving the pipe 11 will be about 52½° F.

As for the condenser, the cooling water which 70 passes through the pipes 17 will enter it at about 70° F., and be warmed to such an extent that when it leaves the other end of the condenser beyond the chamber 3' it will have a temperature of about 98° F. In the chamber 3' the 75

back pressure will be about 2 inches of mercury, in the chamber 4' about 1.71 inches, in the chamber 5' about 1.45 inches and in the chamber 6' about 1.26 inches. Thus as the pressure in the chambers 3, 4, 5 and 6 drops, the back pressure in the respective corresponding chambers 3', 4', 5' and 6' falls also, and the load on each of the ejectors is kept down because of this reduction of back pressure in the chambers of the condenser. Therefore the water vapor taken out of each of the chambers 3, 4, 5 and 6 is compressed at about the same ratio in the condenser 7, this ratio being about 3.15. At the pressure obtained in the various chambers of the condenser the mixture of steam and water vapor will condense or liquefy at temperatures of, say, 101, 96, 91 and 86 in the chambers 3', 4', 5' and 6' respectively, and the temperature of the cooling water in each of these chambers will be below these figures, so that actual liquefaction will be accomplished.

I find further that by apparatus of this character there can be a saving of nearly 300 pounds of steam per hour in a refrigerating plant of 100 tons capacity. Obviously if the evaporator and condenser were not in sections, but each contained only a single chamber, and the same quantity of condenser water were employed, and no greater rise in temperature between the condenser inlet and outlet were allowed, water coming into the pipe 2 could only be cooled down through the same range of temperature (17.5° F.) by first reducing the pressure in the whole evaporator to .4 inches, this being the lowest pressure in the chamber 6, and all the water vapor and steam would have to be forced into the condenser at a back pressure of 2 inches of mercury absolute, which is the back pressure prevailing in the chamber 3'. The compression ratio would thus be much higher and a great deal more steam would have to be consumed.

If, on the other hand, one were to try to operate the system with an evaporator having one chamber and the pressure in that chamber equal to 0.4 inches of mercury, the same as in the chamber 6, and to save steam by using a condenser with a single chamber and keeping the back pressure in this condenser down to the pressure that exists in the chamber 6', much

more water would have to be used to make operation feasible, because this water, instead of being allowed to warm up to 98° would have to leave the condenser at a much lower temperature to prevent the back pressure in the condenser from going up beyond the allowed figure.

The saving of steam is thus effected by extracting the water vapor from the evaporator chamber in which the pressure is highest and discharging this water vapor into the condenser chamber where the back pressure is highest, and proceeding similarly with the other chambers down to the evaporator chamber in which the pressure is lowest so that water vapor from this last chamber is discharged into the condenser chamber wherein the back pressure is least. The operation thus proceeds step by step, the water being cooled in successive stages in the evaporator and the vapor being removed at each stage, compressed to the same ratio and liquefied in the condenser 7.

It will be seen that the apparatus achieves the ends in view by means of a comparatively simple construction, which can be readily and inexpensively built, and easily operated, and it is not likely to get out of order.

I claim:

In condensing apparatus, a series of condenser chambers within a common casing, each chamber having a vapor inlet, means for passing a cooling medium through the chambers, devices having passages to convey condensate successively to each chamber and wherein condensate forms liquid seals between chambers, and means for maintaining individuality of vacuum in each chamber and for removing non-condensable gases therefrom comprising a pump attached to an end chamber above the condensate level and distant from the vapor inlet thereof, conduits connecting adjacent chambers above the condensate levels and distant from the vapor inlets thereof whereby said gases pass successively through the chambers to reach the pump, and a valve in each conduit to control the size of orifice therein thereby to control the vacuum in each chamber by regulating the flow of gases from one chamber to a succeeding chamber.

JOHN KIRGAN.
